METHOD AND APPARATUS FOR MAKING
THERMOPILE

Ernest A. Joerren, Brooklyn, N.Y., and Samuel M. Bagno, Belleville, N.J., assignors to Specialties Development Corporation, Belleville, N.J., a corporation of New Jersey

Filed Feb. 1, 1961, Ser. No. 86,339
8 Claims. (Cl. 156—269)

The present invention relates to lengths of thermopile adapted for use in fire detecting systems, and, more particularly, to a thermopile strip which is an improvement over that disclosed in copending application Serial No. 837,452, filed September 1, 1959, assigned to the assignee of this application, now Patent No. 3,018,311, January 23, 1962, and to apparatus and a method for making the same.

In the aforementioned patent application, a thermopile strip is disclosed which generally comprises two edgewise joined lengthwise extending sections of metals having dissimilar resistivities, and a backing strip of paper or thin cardboard secured to one side of the strip to strengthen and heat insulate the same, the composite strip having staggered slots and slits at opposite edges thereof extending beyond the junction of the sections to provide intermediate portions having a junction thereon and being zig-zag folded in a manner to provide alternate hot and cold junctions on the folded strip.

The disadvantages with such strips are that the covering operation is difficult and requires elaborate mechanism, the strip is difficult to reel up after being folded, and about half of the strip structure is not used in its folded up condition.

Accordingly, the object of the present invention is to provide a simple, practical and economical manner of fabricating cheaper thermopile strips by means of a rapid continuous process which can be carried out by relatively simple apparatus and is not subject to the disadvantages heretofore encountered in folding portions of the strip to produce alternate hot and cold junctions.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description, and is shown in the accompanying drawings, forming a part of the specification, wherein:

FIG. 1 is a fragmentary plan view of a strip composed of dissimilar metals which in response to heat generate an electromotive force.

FIG. 2 is a fragmentary plan view of the bi-metallic strip with a strip of insulating material applied to one side thereof.

FIG. 3 is a fragmentary plan view of the composite strip after being formed with slots.

FIG. 4 is a fragmentary plan view of the slotted composite strip after covering portions of the strip to provide alternate hot and cold junctions.

FIG. 5 is an elevational view partly in section of apparatus including rolls for covering portions of the strip.

FIG. 6 is a sectional view taken along the line 6—6 on FIG. 5.

2

FIG. 7 is an enlarged fragmentary elevational view of one of the rolls.

Referring first to FIGS. 1 to 4 of the drawings in detail, a strip 10 is shown in FIG. 1 which is composed of two lengthwise extending sections 11 and 12, joined edge-wise at 13, of dissimilar resistive metals such as nickel and iron, for example. This strip may have a thickness of about 0.002 inch and a width of about one inch, and long lengths thereof can be produced economically by butt welding suitably dimensioned blocks or bars of nickel and iron together and rolling down the composite block or bar to the desired thickness and width.

In FIG. 2, the strip 10 is shown after a layer 14 of thin paper or other heat and electrical insulating material have been applied on one side thereof. The paper layer preferably is as wide as the strip but may be slightly wider than the strip with its edges evenly spaced from the edges of the strip. The primary purpose of the paper layer is to provide adequate covering or insulation at the back of the strip to enable hot and cold junctions to be established at the front of the strip. The paper layer 14 can be readily applied to the bi-metallic strip 10 by automatic machinery (not shown) including roller means for adhesively coating the strip and/or the layer and roller means for pressing the strip and the layer together to adhesively secure the same.

In FIG. 3, the composite bi-metallic and paper strip is shown after forming substantially rectangular evenly spaced staggered slots 15 at opposite edges thereof. These slots extend widthwise beyond the junction 13 of the metallic sections 11 and 12 to provide intermediate portions 16 having a lengthwise dimension about equal to the lengthwise dimension of the slots and edge sections 17 having a lengthwise dimension about three times that of the intermediate portions. For example, a slot dimension of about 0.25 inch, an intermediate portion dimension of 0.25 inch and an edge section dimension of 0.75 inch may be used.

In FIG. 4, the slotted strip is shown after covering alternate intermediate portions 16 with a film 18 of a mixture of finely divided electrically nonconductive, radiated heat insulating and heat reflective material and an adhesive to thereby provide alternate exposed or hot and covered or cold junctions *h* and *c*, and darkening the exposed or hot junctions *h* with a stripe 19 of black paint or other heat absorbing material to make the thermopile more sensitive to radiated heat.

The film mixture preferably comprises a slurry of asbestos, magnesium carbonate and/or silica gel or the like, and any suitable quick drying or heat dryable resin or adhesive for permanently securing the film 18 on the strip over the cold junctions upon being dried.

In FIGS. 5 to 7, apparatus is shown for applying the film 18 which generally comprises rolls 20 and 21 between which the slotted composite strip (FIG. 3) passes, a tank 22 for a source of slurry 23, means for applying slurry on the roll 21 such as a transfer roll 24 in contact with the roll 21 and passing through the source of slurry, and mechanism for effecting rotation of the rolls 20 including intermeshing gears 25, 26 and 27 rotatable with the rolls 20, 21 and 24, respectively, and a motor 28 having a gear 29 on its driveshaft in mesh with the gear 25.

In order to index the strip with respect to the rolls 20 and 21 and apply the slurry on the intermediate portions 16 to provide the film 18 (FIG. 4), the roll 20 has staggered projections 30 at opposite edges of its working

surface which correspond in dimension and arrangement to the slots 15 and are adapted to extend therethrough; and the roll 21 has similarly dimensioned and arranged recesses 31 on its working surface adapted to mesh with the projections 30 and has applicator surfaces 32 between alternate pairs of recesses 31 corresponding in shape to the area of the film 18 and adapted to contact the roll 24 to receive the slurry to be applied to the strip portions 16. The remainder of the working surface of the roll 21 is provided with shallow recesses 34 between adjacent surfaces 32 which correspond in shape to the portions 16 of the strip to be left uncovered and remain out of contact with the roll 24 so that the slurry is not applied thereto. (FIGS. 6 and 7.)

While the apparatus has been described in connection with providing the film 18, the stripe of paint 19 could be applied in the same manner with almost identical apparatus preferably after applying the film. Such apparatus would be modified only in that the applicator surfaces 32 would correspond in shape and position to stripe 19 and the shallow recesses 34 would correspond in shape and position to the surfaces of the strip not to be coated with the paint.

In order to provide apparatus for continuous inline production of the thermopile, the metallic strip 10 and the backing strip 14 are first united and then passed through a pair of slotting rolls 35 and 36 having punch and counterpunch means 37 and 38 thereon corresponding in shape and location to the projections 30 and the recesses 31 (FIG. 6). The slotted composite strip is next passed through the film providing rolls 20 and 21, is then passed through a pair of stripe providing rolls 39 and 40 shown schematically, and is finally passed through a chamber (not shown) for thoroughly drying the film 18 and the stripe 19 before reeling up the strip.

While the present invention has been illustrated and described with reference to a film-like covering composed of heat insulating material and an adhesive, it will be understood that pieces of paper or the like having the same form as the film 18 could be adhesively applied to the strip to accomplish the same result.

From the foregoing description, it will be seen that the present invention provides a simple, practical, rapid and economical manner of producing an improved thermopile strip.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

We claim:

1. The method of making a thermopile from a metallic strip composed of two edgewise joined lengthwise extending sections of metals having dissimilar resistivities and having alternately staggered slots at opposite edges thereof extending beyond the junction of the sections to provide intermediate portions having a junction thereon, which method comprises applying at one side of the metallic strip a coating of a mixture of finely divided heat insulating material and an adhesive on alternate intermediate portions provided with a junction thereon to provide a cold junction, indexing the metallic strip by means of the slots therein while applying the mixture to properly locate the coating, and drying the mixture to provide a covering secured to the strip.

2. The method of making a thermopile from a metallic strip composed of two edgewise joined lengthwise extending sections of metals having dissimilar resistivities, which method comprises forming alternately staggered slots at opposite edges thereof extending beyond the junction of the sections to provide intermediate portions having a junction thereon, securing radiated heat insulating covering means at one side of the metallic strip on alternate intermediate portions provided with a junction there-

on to thereby provide alternate hot and cold junctions on the metallic strip, the covering means being composed of a coating of a mixture of finely divided heat insulating material and an adhesive to provide the cold junctions, and drying the mixture to provide a covering secured to the strip, said method including the step of indexing the metallic strip by means of the slots therein while applying the mixture to properly locate the resulting covering on alternate intermediate positions.

3. The method according to claim 2, which includes the step of first applying a backing strip to the metallic strip and slotting the same with the metallic strip to facilitate indexing of the metallic strip.

4. Apparatus for applying a covering onto a thermopile strip composed of two edgewise joined sections of dissimilar metals having alternately staggered slots at opposite edges thereof extending beyond the junction of the sections to provide intermediate portions having a junction thereon, which apparatus comprises a first roll, having staggered projections at opposite edges thereof matching the slits of the strip and adapted to extend through the slots of a second roll adjacent said first roll having staggered recesses adapted to mesh with said projections to thereby index the strip between the rolls, said second roll having applicator surfaces between alternate pairs of recesses for applying the covering onto the strip at alternate intermediate portions to provide cold junctions, means for applying the material providing the covering onto said surfaces, and mechanism for effecting rotation of said rolls to move the strip therebetween.

5. Apparatus according to claim 4, wherein said applying means includes a source of the covering material and a transfer roll passing through said source and contacting said surfaces.

6. Apparatus according to claim 4, wherein said second roll has shallow recesses between adjacent covering material applying surfaces which are ineffective to apply the mixture to the strip.

7. Apparatus according to claim 6, wherein said shallow recesses and said surfaces correspond in shape to the surface area of the strip to remain uncoated and to be covered with the material.

8. In apparatus for producing a thermopile from a strip composed of two edgewise joined sections of dissimilar metals, the combination of a pair of rolls for forming alternately staggered slots at opposite edges of the strip extending beyond the junction of the sections to provide intermediate portions having a junction thereon, a means including a pair of rolls for covering alternate intermediate portions with a radiated heat insulating material to provide cold junctions, and means including a pair of rolls for striping the other intermediate portions with a heat absorbing material to provide hot junctions, said pairs of covering and striping rolls having indexing means cooperating with the slots to position the portions of the strip to be covered or striped with respect to said covering and striping rolls.
